UNITED STATES PATENT OFFICE.

EMIL L. JOHNSON AND OLOF LUNDSTEN, OF ATTLEBORO, MASSACHUSETTS.

EXTENSION DEVICE FOR FLEXIBLE BRACELETS.

Application filed September 29, 1926. Serial No. 138,409.

This invention relates to an extension device for flexible bracelets, more particularly watch bracelets for holding a wrist watch on the arm of the wearer and is an improvement in the construction illustrated in our copending patent application Ser. No. 131,900; and the object of this invention is to provide means at each end of a device formed of plurality of foldable sections for releasably holding the sections in closed or folded position.

15 A further object of the invention is to provide a means at an end of one of a plurality of sections which may be snapped into and locked beneath a cooperating overhanging portion of another section and which may be withdrawn from locked position by a swinging of the sections one relative to the other.

20 A still further object of this invention is to provide fingers on one of the end sections for frictionally engaging a pivot pin connecting the other end section and the intermediate section to further assist in holding the sections in closed or folded position.

25 With these and other objects in view, the invention consists of certain novel features of construction, as will be more fully described, and particularly pointed out in the appended claims.

30 In the accompanying drawings:

Figure 1 is a side elevation illustrating the improved device in its relation to a wrist watch and bracelet.

Figure 2 is a perspective view of the under side of the section of the device.

Figure 3 is a perspective view of the intermediate section.

Figure 4 is a perspective view of the gripper member.

40 Figure 5 is a perspective view of the bottom section of the device.

Figure 6 is a central sectional side view of the device.

Figure 7 is a sectional view on substantially line 7-7 of Figure 6.

Figure 8 is a central sectional side view showing the device as partially open or unfolded.

It is found in the use of extension devices for flexible bracelets of the type more especially adapted for use in wrist watches, desirable to provide different sections which are folded one upon the other to snugly hold the watch on the wrist of the wearer and permit the bracelet to be extended for passing the bracelet and watch over the hand of

the wearer, and that under certain unusual strains the sections are apt to separate or become partially unlocked or unfolded, and in order to avoid such objectionable detachment of the parts, we have provided releasable locking means at each end of the device for positively securing the sections against unfolding, and yet which may be readily released to permit the sections to be unfolded to an end to end position to temporarily lengthen the bracelet; and the following is a detailed description of the present embodiment of this invention showing one construction of extension member by which these advantageous results may be accomplished:—

With reference to the drawings, 10 designates a wrist watch which is provided with bails 12 to which portions of a flexible bracelet 13, of leather, mesh fabric or any other suitable material are connected, and the opposite ends of the bracelet are connected to an extension device 14 which is adapted to be unfolded to lengthen the bracelet and which comprises channel shaped end sections 15 and 16 which are connected together through an intermediate section 17 by means of pivot pins 18 extending through the ears 19 and openings 20 in the side walls 21 and 22 of the top and bottom channel shaped end sections, as illustrated. The top section 15 is provided with an end wall 23 which is inclined inwardly providing an overhanging portion beneath which the cam-shaped ends 24 of the side walls 22 of the opposite end section 16 may be snapped by the resiliency between the parts and which may be withdrawn from beneath the end wall 23 by swinging of the end section 16 on the pivot 18 which connects it to the intermediate section 17 by which it will be seen that the end section 16 may be readily removed from its locked position beneath the overhanging portion 23 or which may be positioned between this overhanging portion by a reverse operation to securely hold the section in folded or closed position.

The opposite ends of the walls 22 are formed by undercutting portions thereof to snap beneath the pivot pin 18 and the resiliency of these portions is increased by cutting away portions of the side walls to form slots 26 and leave fingers 25 of great resiliency to snap beneath the pivot pins 18 connecting the intermediate section 17 and the top section 15 to securely hold the free end of the section 16 in folded or closed 105 110

position. In order that the intermediate section will remain in substantially central position between the side walls 21 of the top section spacing members such as projections 27, are provided to extend laterally from the intermediate section 17 and to engage the side walls 21 to so position the intermediate section on the pivot 18 that it will not obstruct the entry of the fingers 25 to engage the pivot pin 18.

10 A gripper 28 having trunnions 29 extending therefrom is pivoted in the opening 30 in the end section 16 and between the gripping edge 31 and the section 16 a flexible bracelet part 13 may be releasably held. A 15 detent 32 is provided on the gripper to engage an opening 33 in the intermediate section to assist in retaining the parts in closed position as is more fully described in our 20 copending application above referred to.

It will be understood that in actual practice the sections will be slightly curved as 25 illustrated in Figure 1, to conform to the wrist of the wearer but as the curvature of the sections perform no functional result in this construction, we have illustrated the sections as formed of straight lines rather than on the arc of a circle. It will be seen from the foregoing that we have provided 30 a construction by which a plurality of sections which may be unfolded to temporarily lengthen the bracelet are positively frictionally held in closed position by which accidental disengagement of the same is avoided.

35 The foregoing description is directed solely towards the construction illustrated, but we desire it to be understood that we reserve the privilege of resorting to all the mechanical changes to which the device is 40 susceptible, the invention being defined and limited only by the terms of the appended claims.

We claim:

45 1. In an extension device for flexible bracelets, a pair of end sections having side walls, an intermediate section pivoted at its opposite ends to the end sections, an inwardly inclined end wall on one of said end sections, a cam shaped portion on the side 50 walls of the other end section extending beneath the said inclined end wall to lock the end sections together, said cam shaped portion being withdrawn from beneath said end wall upon swinging of the same on its 55 pivotal connection to the intermediate section.

60 2. In an extension device for flexible bracelets a pair of end sections, an intermediate section, pivot pins connecting the ends of the intermediate section to the end

sections, fingers on the free end of one of said sections having overhanging portions for releasably engaging the pivot pin connecting the intermediate section and the other of said end sections.

65

3. In an extension device for flexible bracelets a pair of channeled shaped sections, an intermediate section, pivot pins connecting the opposite ends of the intermediate section to the side walls of the channel sections, means carried by one of the sections for spacing the intermediate section from the side walls of one of the channel sections to which it is attached, and fingers on the free end of the other of said channel sections for 70 extending in the space between the intermediate section and channel section and engaging the pivot pin connecting these sections.

75

4. In an extension device for flexible 80 bracelets, a pair of channel shaped sections, an intermediate section, pivot pins connecting the opposite ends of the intermediate section to the side walls of the channel sections, and resilient fingers formed from the side walls of one of said channel sections having overhanging portions for releasably 85 engaging the pivot pin connecting the intermediate section and the other channel section.

90

5. An extension device for a flexible 95 bracelet comprising a pair of end sections, an intermediate section, pivot pins connecting the opposite ends of said intermediate section to said end sections, an inwardly inclined end wall on one of the end sections, cam portions on the end of the other end section to be snapped beneath said end wall and be withdrawn by the swinging of the end section on its pivotal connection to the intermediate section, and fingers on the said 100 other end section having ends formed to snap beneath the pivot pin connecting the intermediate and the first said end sections.

95

6. In an extension device for a flexible 105 bracelet a pair of channel-shaped sections, an intermediate section, means including ears on the intermediate section and pivot pins for connecting the opposite ends of the intermediate section to the side walls of the channel sections, undercut portions at the ends of the side walls of one of said channel sections for releasably and frictionally 110 engaging one of the pivot pins which connects the intermediate section and one of said end sections.

110

In testimony whereof we affix our signatures.

EMIL L. JOHNSON.
